Primary Examiner — Michael A. Pratt*(74) Attorney, Agent, or Firm* — McKee, Voorhees & Sease, PLC(57) **CLAIM**

The ornamental design for a replacement roof top for compact and mid-size sport-utility vehicles, as shown and described.

DESCRIPTION

FIG. 1 is a first perspective view of a replacement roof top for compact and mid-size sport-utility vehicles;

FIG. 2 is a second perspective view thereof;

FIG. 3 is a third perspective view thereof;

FIG. 4 is a fourth perspective view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is a left-side elevation view thereof; and,

FIG. 10 is a right-side elevation view thereof.

The surface of the replacement roof top for compact and mid-size sport-utility vehicles can be transparent.

Structures shown in dash-dash broken lines form no part of the claimed design.
